UNITED STATES PATENT OFFICE.

FRANK KNOEPPEL, OF TOLEDO, OHIO, ASSIGNOR TO THE CHAMPION NO-LEAK PAPER DISH COMPANY, OF TOLEDO, OHIO, A CORPORATION OF OHIO.

CARTON CHARGER.

Application filed June 11, 1927. Serial No. 198,151.

This invention relates to loading goods into containers.

This invention has utility in charging cartons with rows or layers of articles in checked aggregate quantity.

Referring to the drawings:

Fig. 1 is a side elevation from the right of a device embodying the invention hereunder;

10 Fig. 2 is a view from the left of the device of Fig. 1;

Fig. 3 is a plan view of the device of Fig. 1;

15 Fig. 4 is a view from the left of Fig. 1; and

Fig. 5 is a section on the line V—V, Fig. 3.

Bases 1, 2, are provided with uprights 3, 4, having ways 5 vertically extending, 20 parallel, and opposing each other. These uprights 3, 4, provide aligned bearings for rock shaft 6 having thereon cams with short radius portions 7, intermediate enlarging radius portions 8, and long radius portions 9. Hand wheel 10 serves to operate this rock shaft 6 for positioning the cams effective through acting upon projections 11 of supplemental uprights 12 to adjust auxiliary or supplemental table 13. With the hand wheel 10 in position to locate upwardly short radius portion 7 of the two cams, the table 13 is in its lower position. With the hand wheel 10 effective for rocking the shaft 6 to locate upwardly the cam 30 portions 9, the table 13 is in its upper position. There is accordingly effected a vertical shifting of this table 13.

This table 13 has supplemental guide way 14 therein engaged by tongue 15 of support 40 or receiver having bottom 16, side walls 17, 18, and rear wall 19. These walls 16, 17, 18, 19, provide an open top pocket with open side 20 for receiving a carton.

As a carton is placed in position in this receiver, arm 21 is depressed to rock shaft 22 having arm 23 connected by link 24 to arm 25 at integrator or counter 26 having dials 27. Accordingly, at each placing of a carton in this receiver there is a tally or 50 count transmitted to the counter 26 for indication on the dials 27.

Chute or way 28 is shown as horizontally extending with open end 29 adjacent the open side 20 of the pocket. Articles of 55 goods, as food trays 30, in nested series

along the way 28, may be conveniently loaded in this carton 31 by having the open side of such carton 31 disposed toward the way 28.

In the instances that the articles may be placed in a plurality of vertical and a plurality of lateral series in the carton 31, the table 13 may be elevated to bring the lower edge of the carton 31 in approximate registry with the way 28 at one corner of the carton located by lateral or horizontal shifting of the receiver on the supplemental guide. As herein shown the carton may contain four rows of articles 30 in two series. With the table 13 elevated, the receiver is 60 located for sliding one group of the trays 30 directly into the container 31. The receiver may then be shifted laterally, in the still elevated position, to allow a second group of the containers 30 to be placed in 65 the bottom or lower side of container 31 adjacent the first row.

The operator then to lower the receiver kicks or throws the wheel 10 so that the cams have the portions 9 shifted downwardly 30 from the sustaining position and the cam portions 7 are in sustaining position for the projections 11. Above the second group of trays 30, the operator may now shift horizontally into the carton 31 from chute or way 28 a third group of trays 30. To complete the charging of this carton 31, the receiver is given a horizontal shift along the supplemental guide 14 and the fourth group of the trays 30 is placed in a horizontal series 70 above the first placed group. The operator may then lift the carton 31 from the receiver, glue the flaps, or otherwise complete the 75 carton closure as desired.

The placing of a succeeding carton in the receiver operates the arm 21 and thus tallies such for an additional count. This sequence of operations is repeated by the operator lifting the table 13, operating the hand wheel 10 so that cam portions 9 hold the carton 31 in registry with the way 28. This device is such that in producing trays at the rate of above 100 per minute and packing say 500 in a carton, one operator may care for placing the trays in cartons for at 80 least two machines. This means a material reduction of labor with a simplification in the packing of the cartons. There is minimum of labor in lifting, for there is only the placing of the empty carton and the re- 85 90 95 100 105 110

moval of the charged carton, the trays or articles of goods being only slid into position without any lifting required whatsoever. The carton is placed to receive the various 5 series as rows of horizontal groups in a plurality of vertical and lateral lines or series.

What is claimed and it is desired to secure by Letters Patent is:

1. A base having a guide, a supplemental 10 guide carried thereby and relatively reciprocable, and a support movable relatively to and carried by the supplemental guide.
2. A base having a vertical guide, a supplemental horizontal guide carried thereby, 15 and a support movably carried by the supplemental guide whereby said guide provides a plurality of positions for the support.
3. A base having a vertical guide, a two 20 position holder mounted thereby, a supplemental horizontal guide directed by the vertical guide to be positioned by the holder, a supply way, and a support shiftable transversely of the way.
- 25 4. A base having a vertical guide, a two position manually controllable holder mounted by the guide, a supplemental horizontal guide directed by the vertical guide to be

positioned by the holder, a supply way, a support mounted by the supplemental guide 30 and a rock shaft operable for positioning the holder for locating the support at different levels as to the way.

5. A base having a vertical guide, a two 35 position manually controllable holder mounted by the guide, a supplemental horizontal guide directed by the vertical guide to be positioned by the holder, a supply way, a receiver for a container open toward the way and shiftable for different locations as to 40 the way for direct supply of articles into the container from the way in a plurality of series for the different locations.

6. A way, a receiver for a container, and a counter actuator carried by the receiver to 45 be actuated by container movement relatively to the receiver.

7. A way, a shiftable receiver for a container, a counter actuator carried with the receiver to be actuated by container positioning in the receiver, and a mounting for 50 for the receiver permitting shifting of the receiver with the counter independently of actuating the counter.

In witness whereof I affix my signature.
FRANK KNÖEPPEL.
